(57) **CLAIM**

I claim the ornamental design for a strap fitting for a saddle flap of an equestrian saddle, as shown and described.

DESCRIPTION

FIG. 1 is a perspective view from one end of a strap fitting for a saddle flap of an equestrian saddle;

FIG. 2 is a perspective view from one side;

FIG. 3 is a perspective view from one end; and,

FIG. 4 is a perspective view showing a stirrup strap inserted into the fitting.

The portions shown in broken line are for illustrative purposes only and form no part of the claimed design.
